UNITED STATES PATENT OFFICE.

JOHN A. McCORMICK, OF ST. LOUIS, MISSOURI, ASSIGNOR TO COMMONWEALTH STEEL COMPANY, OF GRANITE CITY, ILLINOIS, A CORPORATION OF NEW JERSEY.

RAILWAY-TRUCK CONSTRUCTION.

Application filed March 10, 1927. Serial No. 174,185.

My invention relates to railway rolling stock and consists in an improved truck construction.

The main object of my invention is to provide journal box and pedestal structure in which the box may be lubricated through the pedestal.

While my invention may be embodied in specially designed boxes, it is an additional object of my invention to make use of standard boxes for the purpose mentioned.

A further object of my invention is to modify the truck pedestal structure for use with the other elements of my invention.

In the accompanying drawings which illustrate my invention—

Figure 1 is a section through a car truck pedestal, journal box and axle, and is taken on a line parallel with the longitudinal center line of the truck.

Figure 2 is a horizontal section taken on line 2—2 of Figure 1.

Figure 3 is a side elevation of the pedestal leg and adjacent portion of the box shown in Figures 1 and 2.

Figures 4, 5, and 6 correspond, respectively, with Figures 1, 2, and 3 but illustrate a modified structure.

The pedestal illustrated in Figures 1, 2 and 3 is formed integrally with the wheel piece 1 of the truck frame and has spaced legs 2 and 3 which straddle the journal box upon which rest the equalizers (not shown) carrying the truck frame in the usual manner. Each of the pedestal legs 2 and 3 is shown as being of channel section and provided with a similarly shaped wear plate 6 which may be renewed at intervals to maintain the desired fit between the pedestal and the box 7. The box has ribs 8 which position the same on the pedestals.

The web of the right hand pedestal leg 3 is provided with an elongated narrow opening 9 and a pipe 10 is shown as passing through this opening and into box 7; the cellar 11 in the box being provided with a recess to permit the inward projection of pipe 10. Preferably the pipe 10 extends outwardly and upwardly and mounts an oil cup or other reservoir 12, and it will be noted that the flanges of the pedestal leg are flared as indicated at 13 to accommodate the reservoir 12.

A different arrangement is shown in Figures 4, 5 and 6 in which the side wall 5 of the box 14 adjacent the pedestal leg 15 is provided with a larger opening than the opening

in box 7, and lid 16 is hinged to the box wall at 17 and adapted to be swung upwardly through the opening 4 provided in the pedestal leg 15. This box opening permits access to the interior of the box and its cellar 18, the side wall 19 of the latter being cut away for this purpose and the side wall of the box being provided with a flange 20 around the lower portion of the opening.

With this construction, it is likely that the web of the pedestal leg will be cut away to such an extent that it will be desirable to increase the width of the leg materially in order to compensate for the material removed and such formation of the leg is best indicated in Figure 6 which shows leg 15 as being of substantially greater width than the opposite leg 21.

Either of the constructions described by me tends to eliminate the possible entrance of dirt and water to the journal box which is likely when the lubricant is applied through the top of the box.

In the form shown in Figures 4, 5 and 6 the packing is accessible without removing the cellar from the box and without removing the tie bar 22.

The arrangement does not interfere with the relative vertical movement of the box and pedestal, and with the construction shown in Figures 1, 2 and 3 a standard box may be used by drilling the same to admit the pipe 10. The accessibility of the oil cup 12 and hence the easy renewal and replenishing of the oil supply is apparent.

Various modifications in the details of my device other than those shown may be made without departing from the spirit of my invention, and I contemplate the exclusive use of such variations as fall within the scope of my claims.

I claim:

1. In a journal box adapted to be mounted in a truck pedestal, a pedestal engaging side wall, a pipe attached to said wall and extending outwardly and upwardly therefrom, an oil cup carried by said pipe and discharging into the same, and a cellar in said box having a side wall recessed to permit said pipe to extend into the interior of said cellar.

2. In a railway truck, a pedestal, a journal box slidable vertically in said pedestal, an axle journaled in said box, and means providing access through the side of said box

and the leg of said pedestal to the interior of said box below said axle.

3. In a railway truck, a pedestal, a journal box slidable vertically therein, there being aligned openings in the lower portion of the side wall of said box and the adjacent leg of said pedestal, and a member mounted on said box and closing the opening therein and extending through the opening in said leg.

4. In a railway truck, a pedestal, a standard journal box mounted in said pedestal, and a pipe inserted through a leg of said pedestal and the adjacent wall of said box, the opening for said pipe in said pedestal leg being elongated to permit vertical movement of said box and pipe in said pedestal.

5. In a railway truck, a pedestal, a journal box slidable in said pedestal, a pipe extending from said box through the adjacent leg of said pedestal, said leg being channel-shaped in cross section with its flanges flaring outwardly to accommodate between them an oil reservoir mounted on said pipe.

6. In a railway truck, a pedestal, a standard journal box slidable in said pedestal, a pipe extending from the side of said box through the adjacent leg of said pedestal, said leg being channel-shape in cross section with its flanges extending at right angles to its web for a sufficient distance to clear the flanges on the wall of said journal box and then being inclined outwardly to accommodate an oil reservoir mounted on said pipe and wider than the distance between said flanges at said web.

7. In a railway truck, a pedestal, a wear plate on the inner face of one of said pedestal legs, a journal box slidably mounted in said pedestal, and a pipe inserted through said pedestal leg and wear plate and the adjacent wall of said box, the opening for said pipe in said pedestal leg and wear plate permitting vertical movement of said box relative to said pedestal.

In testimony whereof I hereunto affix my signature this 7th day of March, 1927.

JOHN A. McCORMICK.
